CLEANER FOR GOLF CLUB HEADS OR THE LIKE

Louis J. Postula and Victor A. Postula, Marshall, Mich.,
assignors to Postula Products, Inc., Marshall, Mich., a
corporation of Michigan

Filed Mar. 23, 1965, Ser. No. 84,445

Term of patent 14 years

(Cl. D9—2)

FIG. 1

FIG. 2

FIG. 3

FIGURE 1 is a perspective view showing the top, front, and one side of a cleaner for golf club heads or the like embodying our new design.

FIGURE 2 is a perspective view showing the top, back, and the other side.

FIGURE 3 is a top view thereof.

The broken lines in FIGURE 3 are only shown for illustrative purposes.

We claim:

The ornamental design for a cleaner for golf club heads or the like, substantially as shown and described.
